AUGUST TOELLE, OF ANDERSON, INDIANA, ASSIGNOR TO GENERAL MOTORS CORPORATION, OF ANDERSON, INDIANA, A CORPORATION OF DELAWARE.

CONDENSEL.

Application filed October 13, 1922. Serial No. 594,227.

This invention relates to condensers and the manufacture thereof and includes certain improvements in the type of condenser shown in the copending application of ⁵ Charles E. Wilson and Harry E. Norviel, Serial No. 576,933, filed July 24, 1922.

More specifically it is an object of the invention to provide improved means for securing terminals without soldering to a condenser of the type wherein the condenser foil and insulating material are wound in compact fashion about a central core. One of the objects is to provide a metal core ¹⁰ about which the condenser material is wound and to make this core serve as one of the condenser terminals.

Other and further objects of the present invention will be apparent from the following description, reference being had to the ²⁰ accompanying drawings, wherein a preferred embodiment of the present invention is clearly shown.

In the drawings:

Fig. 1 is a side view of completed condenser mounted upon a support, drawn to full size;

Fig. 2 is a longitudinal sectional view of the condenser on a four to one scale;

Figs. 3 and 4 are end views on a two to one scale showing steps in the manufacture of the condenser;

Fig. 5 is a side view (drawn on a two to one scale) of a condenser end disc shown in section at the left-hand end of Fig. 2;

Fig. 6 is a side view (drawn on a two to one scale) of a condenser end disc shown in section at the right-hand end of Fig. 2; and

Figs. 7 and 8 are sectional and end views, respectively, showing diagrammatically ⁴⁰ mechanism for supporting the core during the winding operation, and the pressure roller.

A brass or other metal core 20 is provided with a reduced end 21 and with a counterbore to provide an annular flange 22 (indicated in original shape by dotted lines), and with a tapped hole 23. This core is mounted in a condenser winding machine of the type disclosed in the copending ap-

plication of F. C. Kroeger and Harry E. ⁵⁰ Norviel, Serial No. 578,513, filed July 29, 1922, with the right end of the core threaded onto the driving center X of the winding spindle and the reduced end 21 supported by the idle center Y of the winding machine indicated diagrammatically in Fig. 7. The core 20 is rotated as indicated by the arrows in Figs. 7 and 8 to wind thereon two strips of foil 24 and 25 separated by paper insulation 26 and 27. Each layer of insulation 26, 27, comprises two or more superimposed strips of thin paper each strip being preferably .0005 of an inch thick. The foil is preferably .0005 of an inch thick. The material is wound on the core under ⁶⁰ 30 to ⁶⁵ 40 pounds pressure applied through roller Z (see Figs. 7 and 8), to form a compact cylinder with the left margin of the foil 25 extending over the left margin of the paper, and with the right margin of the ⁷⁰ foil 24 extending over the right margin of the paper, as shown in Fig. 2.

The method of winding on the condenser material strips is as follows:—

A few turns of the foil strip 24 are first ⁷⁵ wound directly onto the metal core 20 so that this core may provide an electrical connection for this foil strip. Then a few turns of the insulating layer 26 are wound onto the core 20 while the winding on of strip 24 continues. Then the foil strip 25 and the layer 27 are started onto the core with the foil strip 25 next to the layer 26, care being taken that the end of strip 25 is spaced from the strip 24. The core 25 is ⁸⁰ rotated to wind on all of the material simultaneously until a certain number of turns of material are applied. The condenser material foil and paper strips are unwound from supply rolls during this process, and these strips are maintained in a taut condition and with the planes of these strips as near parallel to the axis of the core as possible so as to minimize wrinkling of the material strips as they are wound onto ⁹⁰ 95 the core. The roller Z tends to iron out any wrinkles which may occur and to reduce the air space between the layers of material so

as to obtain compactness without detriment to the condenser material. The strip 24 is severed close up to the core and the other strips an inch or two from the core, so that, 5 when the ends of the strips are wound on, the outer end of strip 24 will be spaced from the outer end of strip 25 and safely insulated therefrom by the insulating strips 26 and 27. A few turns of wrapping paper 28 10 are wound about the core 20, to bring the condenser roll up a certain diameter and the loose end of this paper 28 is pasted down. The paper 28 extends beyond the right margin of foil 24 to assist in providing insulation of foil 24 from the condenser case. 15

After the wrapping paper 28 has been wound on and the loose end pasted down, the condenser is placed within the condenser casing tube or can 30 which has first been 20 formed of a metal sheet bent into the shape 30^a shown in end elevation in Fig. 3. The cylindrical portion of the can 30 is pressed snugly around the condenser as shown in Fig. 4, and the edge 31 is crimped over the 25 edge 32 by means of a suitable tool such as is shown in the copending application of Wilson and Norviel referred to. The seam of the can 30 is soldered and the condenser is impregnated with wax by processes which 30 are generally known to those skilled in the art.

The condenser is now ready for adding ends to the condenser can 30 and for providing suitable terminals.

35 The condenser casing end disc 35 of metal is provided with a square opening 36 to receive the squared shank 37 of a threaded stud 38. When the stud 38 is riveted to the end disc 35, the stud cannot be turned with respect to the disc. The disc 35 is provided with radially disposed sharp ridges 39.

60 The condenser end disc 40 of metal is provided with a center opening 41 through which the core 20 may extend, and with a 65 plurality of points 42.

The method of assembling the condenser can 30 end members is as follows:—

70 The disc 40 is placed over the core 20 with the points 42 projecting inwardly as shown, and the disc 40 mashes down the overhanging edge of the foil 24. The nonconducting washer 43, the condenser casing end 44, nonconducting washer 45 and metal washer 46 are applied in the order shown. Then the 75 right end of the core is pressed against a stationary part by a spinning tool applied to the flange 22 so as to spin this flange over the washer 46 as shown at 48. The left end of core 20 is preferably pressed 80 against a block having a socket to receive the reduced end 21. The can end 44 is soldered to can 30.

85 The disc 35 is pressed into the overhanging edge of foil 25 as shown with the ridges 39 projecting into the mass of mashed foil.

The can edge 47 is crimped over the disc 35 and soldered thereto. The condenser is now ready for mounting upon a suitable support.

While spaces are shown between the end discs and the margins of the foils for sake 70 of clearness of illustration, it should be understood that there are practically no spaces, because the end discs mash the foil into substantially a solid mass.

It is apparent that the core 20 is insulated from the condenser casing and that the two condenser foils have been electrically connected to the core and casing respectively without the use of solder and wires, or terminal strips or such devices 80 that are apt to jar loose in service.

The condenser is one having two spirally disposed foils, the spiral turns of each foil being integral with a mass of oil material. Each condenser foil is like a metallic button 85 having extending therefrom and formed integrally therewith a spiral skirt. Therefore a good electric connection with all parts of the foil strips can be had simply by pressure engagement of the foil and the discs 35 90 and 40.

One method of mounting the condenser is shown in Fig. 1. A suitable nonconducting base 50 is provided with brackets 51 and 52. A screw 53 passes through an aperture in bracket 52 and engages the tapped hole 23 in core 20, and secures a terminal clip 54. The stud 38 projects through an aperture in bracket 51, and a nut 55 is turned down on the stud 38 to secure the condenser in position and to secure a terminal clip 56. Other ways of mounting the condenser and securing conductors thereto will be readily apparent to those skilled in the art. One other method is disclosed in the copending application of F. C. Kroeger, Serial No. 599,238, filed Nov. 6, 1922.

While the form of mechanism herein shown and described constitutes a preferred form of embodiment of the invention, it is 110 to be understood that other forms might be adopted, all coming within the scope of the claims which follow.

What I claim is as follows:

1. In a condenser the combination with 115 two coiled insulated foil strips; of a metallic core upon which the layers of foil and insulation are directly wound, said core being in electrical contact with the inside turn of one foil strip; a cylindrical casing surrounding the foil strips; an end cover for said casing insulated from the core but held by the core against the casing; and an opposite end cover held by the casing in direct contact with the side edge of the second condenser foil strip.

2. An electrical condenser comprising a 120 core having layers of two insulated foil strips wound directly thereupon thus forming a cylindrical body, a metallic cylindrical 125

casing for said cylindrical body, an end cover for said casing held clamped against said casing by said core, an opposite end cover for said casing held in place by said casing, one of said end covers being in electrical contact with one foil strip and serving as the terminal therefor. in electrical contact with the other of said foil strips and serving as the terminal therefor. ¹⁰

In testimony whereof I hereto affix my signature.

AUGUST TOELLE.
